FLAME-HEATER CATHODE TUBE

Quintin J. Wick, Highland, Ill.

Application July 2, 1946, Serial No. 680,913

3 Claims. (Cl. 250—27.5)

1

This invention relates to thermionic tubes, and more particularly to an electron tube wherein thermionic emission is obtained by applying a flame to the cathode to raise it to operating temperature.

A main object of the invention is to provide a novel and improved electron tube device of very simple construction wherein the customary cathode-heating filament is omitted and wherein the cathode is heated by a flame, no electrical power supply being required for heating the cathode.

A further object of the invention is to provide a thermionic tube wherein very high emission is obtained, said tube being relatively small in physical size, being inexpensive to manufacture and having beam characteristics whereby high power handling capability, high power sensitivity and high efficiency are obtained.

Further objects and advantages of the invention will become apparent from the following description and claims, and from the accompanying drawings, wherein:

Figure 1 is a top plan view of a thermionic tube constructed in accordance with the present invention.

Figure 2 is an elevational view of the tube of Figure 1.

Figure 3 is a bottom plan view of the tube of Figure 1.

Figure 4 is an enlarged vertical cross-sectional view of the tube of Figure 1.

Figure 5 is a horizontal cross-sectional view of the tube taken on line 5—5 of Figure 4.

Referring to the drawings, 11 designates a generally cylindrical metal housing or shell to which is secured an axial inner metal tubular member 12, which functions as the cathode of the tube. The space between cathode 12 and shell 11 is hermetically sealed by an annular bottom member 13 of insulating material, said space being evacuated to a very low pressure. Positioned in said space coaxially with cathode 12 is a cylindrical plate 14, and interposed between plate 14 and the cathode and coaxial therewith is a cylindrical grid 15. Grid 15 is connected to a contact prong 16 which passes through bottom member 13 and is secured thereto and plate 14 is connected to a similar contact prong 17. A flame device 18, such as a Bunsen burner, is adapted to be positioned inside cathode 12 to heat said cathode to the temperature required for the thermionic emission of electrons.

Cathode 12 is formed with a plurality of radial corrugations 19 of substantial depth and extending parallel to the axis of the cathode for its en-

2

tire length. The inner crests 20 of said corrugations 19 define heat transmission fins which are closely adjacent the heating flame and serve to localize the regions of high thermionic emission, thereby providing radial, substantially planar electron beams of high electron density which radiate toward plate 14 when said plate is charged with positive voltage. The peripheral portion of cathode 12 also emits electrons but at a lower density, the majority of the electrons being confined to the radial sheets above described. By thus corrugating the cathode, the active emission area is greatly increased, as over a smoothly cylindrical cathode, and the current-handling capability of the tube is considerably magnified.

The flow of electrons from cathode 12 is modulated in the usual manner by signal voltage applied to grid 15.

A further advantage derived from the corrugated cathode employed in the tube is that the inter-electrode capacitance between the cathode and the grid, and between the cathode and the plate is the same as or less than with the smoothly cylindrical cathode, whereas the electron emission of the corrugated cathode is much greater, as above explained. Said emission will be much greater than that obtained in conventional tubes having electrically heated cathodes since much greater heat may be applied to the cathode by the above-described flame method.

Since the cathode is heated by a flame directly applied thereto, no separate electrical power supply for heating the cathode is required.

Although the specific embodiment above described is a triode, the present invention may be applied to any of the conventional tube types employing more than one grid by substituting the flame-heated cathode for the electrically heated cathode employed in the tubes of the prior art.

While a specific embodiment of a flame-activated electron tube has been disclosed in the foregoing description it will be understood that various modifications within the spirit of the invention may occur to those skilled in the art. Therefore it is intended that no limitations be placed on the invention other than as defined by the scope of the appended claims.

What is claimed is:

1. An electron tube comprising an annular metal shell having a non-conducting portion, said shell being hermetically sealed and evacuated, an electrode in said shell, said electrode being spaced from the inner wall of the shell, and a terminal in said non-conducting portion

connected to said electrode, said inner wall being corrugated.

2. An electron tube comprising an annular shell having a corrugated metal inner wall portion and a non-conducting outer wall portion, said shell being hermetically sealed and evacuated, an electrode in said shell, said electrode being spaced from said inner wall portion, and a terminal in said non-conducting portion connected to said electrode.

3. An electron tube comprising an annular metal shell which is generally cylindrical in external contour and having a non-conducting base, said shell being hermetically sealed and evacuated, a plurality of spaced concentric cylindrical electrodes in said shell, the inner electrode being spaced from the inner wall of the shell, said inner wall being formed with a plurality of radial corrugations extending parallel to the axis of the shell and defining a plurality of inwardly extending radial fins, in the hollow center of the shell, and a plurality of terminal prongs carried by said

base, each electrode being connected to a terminal prong.
